CLAIM

The ornamental design for a scooter, as shown and described.

DESCRIPTION

FIG. 1 is a perspective view of a scooter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the scooter where the scooter is in a folded state;

FIG. 10 is an enlarged view of area "10" in FIG. 1;

FIG. 11 is an enlarged view of area "11" in FIG. 1;

FIG. 12 is an enlarged view of area "12" in FIG. 3; and,

FIG. 13 is an enlarged view of area "13" in FIG. 7.

The broken lines in the drawings depict portions of the scooter that form no part of the claimed design. The dash-dot broken lines shown in FIGS. 1, 3, 7, and 10-13 are for the purpose of indicating the enlarged partial views and form no part of the claimed design.
